V. W. THOMAS

TIMER ELEVATOR FOR FORD CARS

Filed Feb. 21. 1921

Inventor:
Victor W. Thomas
By Benjamin Goodlance & Son
Atty.

UNITED STATES PATENT OFFICE.

VICTOR W. THOMAS, OF WAUKEGAN, ILLINOIS.

TIMER ELEVATOR FOR FORD CARS.

Application filed February 21, 1921. Serial No. 446,641.

To all whom it may concern:

Be it known that I, VICTOR W. THOMAS, a citizen of the United States, residing at Waukegan, in the county of Lake and State 5 of Illinois, have invented a new and useful Improvement in Timer Elevator for Ford Cars, of which the following is a specification.

My present invention relates to the provision 10 of a timer elevator for Ford cars. Such a structure is for the purpose of elevating the timer from the front end of the cam-shaft, where it is as present located, to a position where it will be more accessible and 15 will be in a position where it will be less liable to fouling from grease from the motor and from the road dirt either splashed upon it or thrown upon it by the draft created by the fan as its present location is directly 20 behind the fan.

It is not unusual for the cam-shaft to either have originally or develop an appreciable longitudinal movement or end-play, and the cam-shaft is not uniformly positioned 25 with respect to the bolts for holding on the cover plate for the timing gears, through which plate the cam-shaft extends. As the timer elevator is most conveniently secured in position by bolts fitting into the 30 same bolt holes which are at present used for holding the timing gears cover plate in position the variation in the location of these bolt holes with respect to the cam-shaft is liable to effect the operation of the timer 35 elevator.

The particular object of my present invention is to provide a timer-elevator structure, the operation of which will not be affected by end-play in the cam-shaft, and 40 which may be located with respect to the cam-shaft and independently of a variation in the location of its points of attachment.

I prefer to attain the aforementioned objects by means of the structure illustrated in the accompanying drawings, in which—

Figure 1 is a front elevation of a structure embodying my invention showing its relation to the cover plate of the timing gears.

Figure 2 is a vertical section on line 2—2, Figure 1, and

Figure 3 is a vertical section on line 3—3, Figure 2.

Similar reference characters refer to 55 similar parts throughout the several views.

The bracket for effecting the elevation of

the timer comprises a lower portion 4 of cylindrical box-like form, the lateral edge 5 of which approximately coincides with the form and size of the timer casing which is 60 to be elevated, and which seats, or approximately seats, in the seat 6 provided in the timing gears cover plate 7. Arising from portion 4 is a substantially vertical extension 8, the upper end whereof is horizontally 65 extended to form a platform 9 for receiving and supporting the timer casing 10, which has been removed from about the end of the cam-shaft 11.

A bored and interiorly threaded cap 12 70 is provided which is screwed upon the already threaded end of the cam-shaft. This cap has provided upon its circumference a spiral gear 13, and upon its outer end is a reduced slightly extended portion 14, which 75 enters a socket 15 in the inner face of the end of the box-like cylindrical portion 4 of the bracket. The extended portion 14 on the spiral gear, together with socket 15 establishes the desired location of the bracket 80 with respect to the cam-shaft.

The ends of the vertical portion 8 of the bracket are bored, at 16 and 17, to provide journals for a vertical shaft 18, the upper end whereof extends above the table or platform 9 to receive the rotating element 19 of the timer. Upon the lower end of the vertical shaft 18 and with a lateral enlargement 4 of the portion 4 of the casting is 85 mounted a spiral gear 20 which meshes with spiral gear 18 and serves to cause the rotation of the vertical shaft. The employment of spiral gears between the cam-shaft and the vertical shaft eliminates any possibility of jamming or disarrangement of the interaction of these parts through or by reason of 90 end-play in the cam-shaft.

The bracket is further provided with lateral arms 21, 22 and 23, which extend opposite three of the bolt holes in the timing gears cover plate, and these arms are bored with holes somewhat larger than bolts 24 which are to pass through them so that the bracket will be located with relation to the cam-shaft and not by reason of its 100 points of attachment.

The oil which works through from the engine or motor casing will serve to lubricate the spiral gears and the lower journal of the vertical shaft, or the spiral gears 105 casing may be packed with a suitable bearing grease. A grease cup 25 is provided for

lubricating the upper journal of the vertical shaft.

The timer casing 10 is held upon the platform 9 by means of a spring 26 extending from the top of the timer casing to a stud 27 arising from the platform, to which stud the spring is secured by a screw 28.

What I claim new is:

1. Means for mounting and actuating a timer for ignition system of an internal combustion engine comprising a centrally bored and interiorly threaded spiral gear having an axial extension thereon, a casing having a socket for receiving the extension upon said gear, a shaft journaled in said casing, a second spiral gear mounted upon said shaft and within said casing, an extension from said casing terminating in a timer casing platform located adjacent and surrounding the outer portion of said shaft, and arms extending from said casing for securing the same as located through the interfitting of said first-mentioned gear with said casing.
2. Means for mounting and actuating a timer for ignition system of an internal combustion engine comprising a centrally bored and interiorly threaded spiral gear having an axial extension thereon, a casing

having a socket for receiving the extension upon said gear, a shaft journaled in said casing, a second spiral gear mounted upon said shaft and within said casing, an extension from said casing terminating in a timer casing platform located adjacent and surrounding the outer portion of said shaft, and arms extending from said casing for securing the same in desired position.

3. Means for mounting and actuating a timer for ignition system of an internal combustion engine comprising a spiral gear gear adapted to be mounted upon the end of the cam-shaft of the engine and having an axial extension, a casing having a socket for journaling the extension of said gear whereby said casing is located and a bearing is provided for the outer end of the cam-shaft, a shaft journaled in said casing, a second spiral gear mounted upon said shaft and meshing with said first-mentioned gear, an extension from said casing terminating in a platform through which said shaft extends, and arms extending from said casing to secure said casing as positioned through the interfitting of said first-mentioned gear therewith.

VICTOR W. THOMAS.
